UNITED STATES PATENT OFFICE.

CHARLES L. GOODRUM, OF NEW YORK, N. Y., ASSIGNOR, BY MESNE ASSIGNMENTS, TO
WESTERN ELECTRIC COMPANY, INCORPORATED, A CORPORATION OF NEW YORK.

TRANSMISSION SYSTEM.

1,252,427.

Specification of Letters Patent.

Patented Jan. 8, 1918.

Application filed October 8, 1915. Serial No. 54,740.

To all whom it may concern:

Be it known that I, CHARLES LANE GOODRUM, a citizen of the United States, residing at New York, in the county of New York and State of New York, have invented certain new and useful Improvements in Transmission Systems, of which the following is a full, clear, concise, and exact description.

10 This invention relates to a system for establishing communication between a moving train and a central or despatcher's station, and is particularly applicable for such purpose where the block signaling system is in 15 force.

In accordance with this invention there is provided a comparatively inexpensive wireless equipment on each train. An aerial conductor paralleling the track is located in 20 convenient proximity thereto. This conductor is divided into sections preferably corresponding to the number of block sections. Each of these sections is adapted to be connected inductively to a balanced pair 25 of wires by the closure of a contact controlled by a semaphore signal, which is actuated upon the entrance of a train into a given section. Impulses sent out by wireless are communicated to a given section of 30 the aerial conductor, which effects the transmission thereof over the balanced pair of wires to the central or despatcher's office.

The object of this invention is to provide means whereby it is possible to communicate 35 with a moving train partly by wireless and partly by the agency of metallic conductors, thereby making the despatching of trains, while in motion, reliable and commercially possible.

40 At the present time it is possible to communicate with a moving train from a central station by means of wireless apparatus. However, this has not been successful from a commercial standpoint because it is necessary to equip each train with a very expensive wireless apparatus in order to obtain anything like an effective range of transmission; also when a train enters a tunnel, communication therewith is seriously interfered with, if not impossible, for reasons well known to the art of wireless telephony.

It has also been proposed to establish communication between a moving train and a despatcher's office by static induction

through the medium of suitable apparatus 55 carried by the train for inducing a current between a conductor running in close proximity to the track rails and a metallic conductor or covering upon the train. This system proved objectionable from several 60 standpoints, one of which was that the noise produced in the conductor parallel with the track, caused by foreign sources of current having an inductive effect upon said conductor, reached a considerable magnitude 65 due to the length of said conductor.

The accompanying drawing illustrates diagrammatically one of the arrangements by which this invention may be effectuated.

In the drawing there is shown a vehicle 70 or car 1 adapted to travel over track rails 2. The roadbed is divided into sections 3, 4 and 5, as is usual when a block signaling system is in force. Located at each track section is a signaling mechanism 6 provided 75 with a semaphore 7, which mechanism may be of any standard well-known construction which is adapted to be actuated by the passing of a car over the section controlled by a particular one of said mechanisms. Paralleling the track rails and located in close proximity thereto is an aerial conductor 8, preferably having both of its ends grounded. The conductor 8 is inductively connected by means of an inductorium 9 to a 80 balanced pair of wires 10, which extend along the roadbed and to a central office. At the central office there is located apparatus for transmitting and receiving telephonic messages. This apparatus which is 90 shown within the dotted rectangle 14 is of the type disclosed in Fig. 1, of the De Forest Patent No. 1,042,205, the ground and aerial ends of the antenna A⁸ thereof being connected respectively to the line conductors 10. 95 Since this transmitting and receiving apparatus is fully described in the De Forest patent, further description here is considered unnecessary. The circuit of the wires 10 is normally open, and is adapted to be 100 closed upon the closure of contact 11 when the semaphore 7 assumes an operated position. The car 1 is furnished with apparatus for transmitting and receiving telephonic messages by wireless, which is illustrated 105 diagrammatically by the dotted rectangle 12. This apparatus may be of the form shown within the dotted rectangle 14. The

car 1 is equipped with an antenna 13 which may be secured to the roof of the car or in any other convenient location. This antenna 13 corresponds to the antenna A³ of Fig. 1, of the De Forest patent hereinbefore referred to.

The operation of the transmission system contemplated by this invention may best be understood by assuming that the 10 car 1 has passed from section 4 into section 3, and upon the passage of said car into section 3 the block signaling mechanism 6 was actuated, thereby causing the semaphore 7 to effect the closure of a contact 11. This 15 places the aerial conductor 8 in inductive relation with the central station or despatcher's office by means of the balanced pair of wires 10. As the car 1 travels along the track, by virtue of the wireless equipments 12 carried thereby, electrical impulses may be transmitted to the conductor 8, which are conveyed to the despatcher's office over the balanced pair of wires, and there translated by suitable message-receiving 20 apparatus. Messages may be transmitted from the despatcher's office to the car in the same manner, only in the reverse order.

From the above it will be seen that in accordance with this invention a message may 25 be transmitted to a moving train partly by wireless and partly by wire. The object of dividing the aerial conductor 8 into sections corresponding to the block sections is to overcome any objectionable noise which 30 may be induced on conductor 8 by foreign sources of current, which ordinarily come into close proximity thereto at various places along the railway, and if such conductor was continuous instead of being sectional, the magnitude of these induced 35 noises would be considerable upon a long conductor. Having the conductors 8 divided into sections and inductively connected to a balanced pair of wires substantially eliminates any noises which may be 40 picked up in the manner just described.

In view of the above it will be apparent 45 that the wireless apparatus 12, carried by the car 1, need not have a large range of transmission, thus considerably reducing the cost of similar apparatus in systems where communication is established entirely by wireless. At the same time the range of 50 transmission of the wireless apparatus 12 will be sufficient to permit the location of the conductor 8 at a convenient distance from the track rails 2, so as not to interfere with the operation of trains on the railway system. By virtue of the transmission qualities of the wireless apparatus 12, electrical 55 impulses may be transmitted a greater distance through space than is possible by a means of static induction.

What is claimed is:

65 1. In a transmission system, the combina-

tion with a block signal mechanism having a semaphore arranged to be actuated by the passage of a car over the track section governed by said mechanism, of an aerial conductor paralleling said track and in close proximity thereto, a car or vehicle traveling on said track section, means carried by said car for impressing electrical impulses upon said conductor, and means for conveying said impulses to a central office, said means including a balanced pair of wires extending along the track and having their circuit normally opened at a contact controlled by said signal mechanism.

2. In a transmission system, the combination with a block signal mechanism having a semaphore arranged to be actuated by the passage of a car over the track section governed by said mechanism, of an aerial conductor paralleling said track and in close proximity thereto, a car or vehicle traveling on said track section, means carried by said car for impressing electrical impulses upon said conductor, and means for conveying said impulses to a central office, said means including a balanced pair of wires extending along the track from a central station, said wires being inductively connected to said conductor, and means controlled by said semaphore for interrupting the circuit of said balanced wires.

3. In a transmission system, the combination with a block signal mechanism having a semaphore arranged to be actuated by the passage of a car over the track section governed by said mechanism, of a balanced pair of wires adapted for telephone purposes extending along the track from a central station, said wires being associated with said signal mechanism and having their circuit normally opened, a contact controlled by said semaphore for closing the circuit of said wires, a car or vehicle traveling on said track section, said car being furnished with a wireless equipment, an aerial conductor paralleling said track and in close proximity thereto, said conductor being inductively connected to said balanced pair of wires whereby communicating may be established between said car and said station upon the closure of said contact.

4. In a transmission system, the combination with a plurality of block signal mechanisms each having a semaphore arranged to be actuated by the passage of a car over the track section governed by a given one of said mechanisms, of a balanced pair of wires adapted for telephone purposes extending along the track from a central station, said wires being associated with said signal mechanism and having their circuit normally opened, means individual to each of said semaphores for closing the circuit of said wires, a car or vehicle traveling on one of said track sections, said car being fur-

nished with a wireless equipment, an aerial conductor paralleling said track and in close proximity thereto, said conductor being divided into sections corresponding in number 5 to said signaling mechanism, said conductor being inductively connected to said balanced pair of wires whereby communication

may be established between said car and said station upon the closure of any of said contacts.

In witness whereof, I hereunto subscribe my name this 5th day of October, A. D. 1915.

CHARLES L. GOODRUM.
